UNITED STATES PATENT OFFICE.

SAMUEL H. MOWREY, OF PHILADELPHIA, PENNSYLVANIA.

FOLDING STOOL.

1,325,164.

Specification of Letters Patent. Patented Dec. 16, 1919.

Application filed July 11, 1919. Serial No. 310,205.

To all whom it may concern:

Be it known that I, SAMUEL H. MOWREY, a citizen of the United States, residing at Philadelphia, in the county of Philadelphia and State of Pennsylvania, have invented 5 certain new and useful Improvements in Folding Stools, of which the following is a specification.

This invention relates to stools of that 10 class known as folding, and the broad purpose of the invention is to produce an article of this kind wherein the several elements are separable and may be housed within the seat, the latter being of such construction 15 as to present the appearance of a small suitcase.

The structure includes a collapsible base, a collapsible head, a pedestal separably connecting these elements, and a foldable or 20 box-like seat capable of being mounted on the head.

The invention consists in the details of construction more fully set forth below. Referring to the drawings:

25 Figure 1 is a perspective view of this stool set up ready to use, and Fig. 2 is a perspective view showing the device completely folded so that it may be carried in the hand.

Fig. 3 is a central vertical section.

30 Fig. 4 is a bottom plan view of the seat distended.

Fig. 5 is a sectional detail on the line 5—5 of Fig. 3.

Fig. 6 is a perspective detail of the upper 35 end of one of the arms.

Fig. 7 is a sectional detail showing the hinge connection between the leaves of the seat.

The base as herein shown comprises four 40 legs 1 pivoted near their upper ends at 2 within radial slots 3 in a hub 4 having a central upright bore 5.

The pedestal includes a body 11 shouldered at its upper and lower ends as at 12, 13 and having pins 14 and 15 extending beyond 45 said shoulders, the pin 15 fitting rotatably within the bore 5 of the hub 4 when the parts are assembled as seen in Fig. 3.

The head in the present instance comprises 50 four arms 21 pivoted at 22 within radial slots 23 in a hub 24, the hub having a bore 25 through which may pass the upper pin 14 when the parts are assembled as seen in Fig. 3. The upper end of each arm is cut away 55 along its opposite sides to produce shoulders 26 between which the material of the

arm is continued into a tongue 27 preferably slightly dove-tailed as seen in Fig. 6 and having its upper end 28 cut off on a line oblique to the length of the arm as shown. 60

The seat is made up of three leaves connected edge to edge by knuckle joints as shown at 30, and for sake of distinction we will call the intermediate leaf a panel 31 and the other and rather wider leaves sides 32 65 because they form the sides of the casing when closed as seen in Fig. 2, having flanges 33 around three of their edges which come together to make up the box-like whole. A catch 34 fastens the casing closed, and one 70 side member may carry a handle 35. Centrally pivoted at 36 to the lower face of the panel 31 is an elongated button or bar 37 having near its opposite ends grooves 38, and the panel itself is provided in its lower 75 face near its opposite ends with similar grooves. The latter have mouths of a shape similar to key-hole slots, their larger ends being disposed toward the pivot 36, and internally they are of a cross section which 80 will fit the shape of the dove-tailed tongues 27. The several leaves of the seat may be painted or ornamented externally, or may perhaps carry a fabric or even an upholstered covering. The parts are of the desired materials which will afford sufficient 85 strength to support the user.

The stool is shown in Fig. 1 set up ready for use, and at this time the hub of the head will swivel around the upper pin 14, which 90 for sake of greater strength will pass upward into a socket 39 produced by countersinking the screw 36. Also the pedestal will swivel within the hub 4 of the base, and therefore the user is mounted on a pivot 95 stool. When the device is no longer desired for use, the pedestal is lifted out of the base and the legs folded, the upper pin of the pedestal pulled out of the hub 24, said hub moved downward to draw the several arms 100 inward and their tongues 27 downward from the several grooves 38 so that the arms may be all folded together, then the cross bar or long button 37 is turned on its pivot 36 into alinement with the central leaf or panel 105 31, and the remaining parts stacked in the casing which is closed and latched as shown at 34. For holding said parts within the casing, one or both the sides 32 thereof may have straps or strip metal springs 40 beneath which the movable parts will be inserted. When the operator again desires 110

to use the device as a stool, he unlatches and opens the casing, removes the loose parts, turns the button 37 to the position shown in Fig. 4, and reassembles the elements in a manner which will be clear. While both pins 14 and 15 are shown round, it is clear that a swivel effect would result if only one were round, but it is much cheaper and just as satisfactory to turn down both ends of the pedestal into round pins and bore both hubs with round holes, as it would be to make one of the pins and one of the holes of other shape. It is preferred that the arms be four in number, two of which engage the sockets in the middle leaf, while the other two engage the sockets in the cross bar or button, and the latter supports the outer leaves, but it is not at all essential that there shall be four legs in the base. In fact, the base of the structure is capable of extended modification without departing from the principle involved, and the exact form of pivots in both the base and the head is immaterial. Also I have shown a set screw 43 in Fig. 4 and set screws 44 and 45 in Fig. 1, which may be employed for holding the parts together when assembled, but these set screws are omitted from Fig. 3. Other changes also may be made by the manufacturer, consistent with the claims below.

In closing it is hardly necessary to add that, while this device has been described as a stool on which the user is to sit, it might readily be utilized as a table, as on automobile trips or pedestrian hikes, or it could be used as a flower stand, taboret, etc. Therefore the term "seat" as employed herein should be read in conjunction with the device when used as a stool.

Having thus described the invention, what is claimed as new is:

1. In a collapsible structure of the type described, the combination with a base, a pedestal, and a head mounted on the pedestal and including a plurality of pivoted arms having tongues at their upper ends; of a seat made up of three leaves hinged together edge to edge, and a cross bar centrally pivoted beneath the intermediate leaf and of a length to underlie the others when turned on its pivot across the several leaves, said bar and intermediate leaf having

sockets shaped to detachably receive the tongues on said arms. 55

2. In a collapsible structure of the type described, the combination with a base, a pedestal, and a head mounted on the pedestal and including a plurality of pivoted arms having tongues at their upper ends; of a seat including a narrow panel and two wide leaves, knuckle hinges connecting them, flanges along the outer edges and ends of the leaves, those on one leaf abutting those on the other when the seat is folded; and a bar adapted to extend across beneath the panel and both leaves, said bar and panel having sockets near their ends for detachably receiving the tongues on said arms. 60 65

3. In a knock-down structure of the type described, the combination with a collapsible base including a tubular hub, a collapsible head including a tubular hub and four arms pivoted at their lower ends thereto, and a pedestal whose body is reduced and shouldered at both ends and continued beyond the shoulders into upper and lower pins adapted for removable engagement with said hubs; of a folding seat of box-like structure adapted to contain the other elements when disconnected and collapsed, the seat having a central socket for the upper end of the upper pin and other sockets for the upper ends of said arms. 70 75 80

4. In a knock-down structure of the type described, the combination with a collapsible base including a tubular hub, a collapsible head including a tubular hub and four arms pivoted at their lower ends thereto, and a pedestal whose body is reduced and shouldered at both ends and continued beyond the shoulders into upper and lower pins adapted for removable engagement with said hubs; of a seat made up of three leaves hinged together edge to edge, the side leaves having flanges coacting in the folding of the seat to produce a box-like casing for receiving the other elements, and a bar pivotally mounted on a screw countersunk through its center and into the intermediate leaf, thereby leaving a socket for receiving the upper end of the upper pin, the bar and the intermediate leaf having other sockets for the upper ends of said arms. 90 95 100

In testimony whereof I affix my signature. 105
SAMUEL H. MOWREY. [L. S.]
